UNITED STATES PATENT OFFICE.

CHARLES A. BRYANT, OF WAKEFIELD, MASSACHUSETTS.

SOAP-HOLDER.

SPECIFICATION forming part of Letters Patent No. 316,734, dated April 28, 1885.

Application filed September 5, 1884. (No model.)

To all whom it may concern:

Be it known that I, CHARLES A. BRYANT, of Wakefield, in the county of Middlesex and State of Massachusetts, have invented a new 5 and useful Improvement in Soap-Holders, of which the following is a full, clear, and exact description.

Soap-holders have heretofore been made consisting of perforated receptacles provided with 10 handles.

In my improved holder the receptacle or soap-box is fitted for rapid rotation, whereby the soap is more quickly dissolved to the extent desired, as hereinafter described.

15 Reference is to be had to the accompanying drawings, forming a part of this specification, in which similar letters of reference indicate corresponding parts in all the figures.

Figure 1 is a perspective elevation of my 20 improved device. Fig. 2 is a sectional elevation of the holder in modified form. Fig. 3 is a detail section of the nut. Fig. 4 is a plan view of the box. Fig. 5 is an end view of the nut, and Fig. 6 shows a modified form of handle.

25 A is the handle formed by the doubled end of wire B, as in Fig. 1, or of wood, as in Fig. 2, with wire B inserted. The lower end of wire B is bent at one side and then upward to receive the flanged thimble a. The frame receiving the soap-box C is formed of a wire, D, bent double, twisted in its upper portion, and entered at its upper end into a tube, d, on wire B, Fig. 1, or into the wood handle, Fig. 30 2. Its lower portion is firmly locked to thimble a by passing through the two opposite holes in the flange and bent to fit the grooves in the top of the thimble, which turns with frame D on the end of wire B.

The soap-box C is formed of wire cloth or 40 any perforated material, and has a flanged band, e, of sheet metal around the edge, through which wire D passes, and the sides and bottom of the box are creased to receive the wire and thimble.

45 On the flange of band e is a cover, f, notched at g to allow it to pass the projections h on the band when the cover is to be removed, and held in place at other times by the projections h. i is a nut sliding on wire B and fitting the 50 twisted portion of wire D. By moving nut i up and down while the device is held in hand by handle A the wire D and soap-box C are caused to rotate rapidly in alternate directions. The currents and agitation of the water thus caused are most effective in dissolving the soap and carrying out the dissolved portions.

55 The handle may be made in the form shown in Fig. 6, so as to occupy less space in length.

60 It will be understood that in this application I make no broad claim to the use of the twisted wire rod with its actuating-nut, the same being embodied in a concurrent application of mine for an egg-beater.

65 Having thus described my invention, I claim as new and desire to secure by Letters Patent—

In a soap-holder, the twisted wire with its strands parted or spread apart at the lower end, in combination with the receptacle having the thimble connected to it centrally of its bottom, the rod with its lower end entering said thimble, and the actuating-nut, substantially as and for the purpose set forth.

CHARLES A. BRYANT.
